UNITED STATES PATENT OFFICE.

KATE J. COLLINS, OF NEW YORK, N. Y.

PAPER BOX.

SPECIFICATION forming part of Letters Patent No. 380,861, dated April 10, 1883.

Application filed March 7, 1887. Serial No. 239,986. (No model.)

To all whom it may concern:

Be it known that I, KATE J. COLLINS, a citizen of the United States, residing in the city, county, and State of New York, have invented 5 certain new and useful Improvements in Paper Boxes; and I do hereby declare that the following is a full, clear, and exact description of the invention, which will enable others skilled in the art to which it appertains to 10 make and use the same.

This invention relates more especially to 15 "paper boxes," so called, but may be embraced in the construction of boxes made of any other suitable sheet material, and the term "paper" 20 as herein employed is intended to include other usual and suitable equivalent materials employed in the construction of boxes from sheets folded to form the bottom and sides of the box, so that the said parts are integral the one with 25 the other.

My invention comprises certain novel combinations of parts, whereby a cheap, easily-manufactured, and ornamental box of the class 30 specified is obtained, and one especially adapted 25 for the display of confectionery or other light or fancy articles for sale.

Figure 1 is a perspective view of a box made 35 according to my invention, and Fig. 2 is a face view showing the blank and the parts thereof 40 from which, when folded to suitable rectangular shape, the box is formed. Fig. 3 is a detail horizontal sectional view taken through one corner of the completed box and in the line $x x$ of Fig. 1.

In Fig. 2, a indicates that part of the blank 45 which forms the bottom of the completed box; $b b$, the parts which form the ends thereof; c , the part which forms the front; d , the part which forms the back thereof, and e the part 50 which forms the cover. Upon the lateral edges of the parts $b b$, c , and d , and integral therewith, are lips a' , and upon the remaining edges of the parts $b b c$, and integral therewith, are leaves b' . Upon the free edges of 55 the cover e , and integral therewith, are flaps c' . The said parts are indicated by the same reference-letters in Fig. 1, in which they appear in position in the completed box.

To form the box from the blank, the parts 60 $b b$, c , e , d , and e are folded upon the lines indicated in Fig. 2 to the relative positions shown in Fig. 1—in other words, to the rect-

angular shape of the box desired. This done, the lips a' at each corner are lapped one over the other, so that the perforations a'' in the one 55 will coincide with the perforations b'' adjacent to the other. This done, the lips so arranged in relation with each other are laced together by cords or lacings f , passed through the perforations athwart the corners formed by the 60 overlapping lips, as shown in Figs. 1 and 3, and the lacing being duly knotted, as indicated at e'' , the corners of the box are firmly 65 united and the lacing crossed on the outside, as illustrated in Fig. 1, which provides a neat 70 ornamentation to the corners, which may, if desired, be heightened by leaving the ends of the lacings of sufficient length to form tassels dependent from the knots e'' . The leaves b' are turned inward to a horizontal position, 75 and their edges being duly indented or made of any desired ornamental configuration, said leaves provide an ornamental covering around the upper circumference of the contents of the box, and this enables the usual lace paper to 80 be dispensed with. The part e is bent forward and downward along a line from the one upper rearmost corner of the box to the other, and its flaps $c' c' c'$ are bent downward to form 85 an ornamental rim, which, when the box is 80 closed, passes around and outside of the upper edges of the front and ends. The blank is provided in a direction transverse to the axis of movement of the cover with a series of holes, f'' , through which alternately inward 90 and outward is passed a locking-string, g , one end of which projects from the front of the box, while the other extends from at or near the front of the cover, so that when the latter is 95 shut down to close the box the two ends of 90 said locking string g may be tied together to hold the box in a closed condition.

It is of course to be understood that the relative proportions at the sides, ends, bottom, and cover of the box may be varied without 95 departing from my said invention. Thus, for example, the box may be made long and narrow at the bottom, or with the bottom curved in its cross-section, as in that class of paper boxes sometimes termed "hampers," and the 100 like.

What I claim as my invention is—

1. A paper box having perforated lips a' , and folded to shape with said lips overlapping

at the corners, and lacings *f*, passed through the perforations of the lips and athwart the corners of the box, substantially as and for the purpose herein set forth.

5 2. A paper box having leaves *b'* integral therewith and arranged to fold inward over the interior of the box, lips *a'*, integral with the blank and arranged to overlap at the corners of the box, and flaps *c'*, integral with the blank and arranged at the free edges of the cover, substantially as and for the purpose herein set forth.

15 3. A paper box having holes *f''*, and with perforated lips *a'* integral therewith and overlapping at the corners of the box, lacings *f*, passed through the perforations of the lips and athwart the said corners, and a locking-string, *g*, passed through the holes *f''* in the body and cover, substantially as and for the 20 purpose herein set forth.

4. A paper box having the locking-string *g* and lacings *f*, with a blank folded to shape provided with holes *f''*, and having integral therewith the perforated lips *a'*, leaves *b'*, and cover *e*, provided with flaps *c'*, substantially 25 as and for the purpose herein set forth.

5. In a paper box, the combination, in a blank having lips *b'* integral therewith and arranged to fold inward over the interior of the box, and perforated lips *a'*, arranged to overlap and be secured at the corners by fastening devices passed through the perforations of said lips *a'*, substantially as and for the purpose herein set forth. 30

KATE J. COLLINS.
